INFANT'S TRAINING CHAIR

E. Burton Benjamin, Highland Park, Ill., assignor to
Welsh-Co., St. Louis, Mo.

Filed Oct. 9, 1970, Ser. No. 25,404

Term of patent 14 years

Int. Cl. D23—02

U.S. Cl. D23—53

FIG. 1

FIG. 3

FIG. 2

FIG. 5

FIG. 4

FIG. 6

FIG. 1 is a perspective view of an infant's training chair showing my new design;

FIG. 2 is a rear elevational view thereof;

FIG. 3 is a front elevational view thereof;

FIG. 4 is a top plan view thereof;

FIG. 5 is a bottom plan view thereof; and

FIG. 6 is a side elevational view thereof.

I claim:

The design for an infant's training chair, substantially as shown.
